TREATMENT OF NATURAL GASOLINE

Harrison L. Hays, Bartlesville, Okla., assignor to
Phillips Petroleum Company, a corporation of
Delaware

Application June 9, 1941, Serial No. 397,296

5 Claims. (CL. 196—50)

The present invention relates to the manufacture of high octane aviation gasoline and high octane number motor fuel by the treatment of natural gasoline in such a manner that substantially all hydrocarbons lying within this range are utilized and converted into highly valuable products.

High octane number hydrocarbons are known for their efficiency and improved performance as fuels for internal combustion engines. It is also known that such high octane fuels reduce the detonation property and allow much higher compression ratio and consequently greater power and the higher speeds demanded of modern airplane engines. Likewise it has been demonstrated that olefin hydrocarbons are of higher octane number and consequently have higher anti-detonation qualities than corresponding straight chain hydrocarbons. The various individual hydrocarbons of the same molecular weight also differ widely among themselves as to detonation or combustion properties, which may be exemplified by the detonation characteristics of normal hexane as compared to 2,2-dimethyl butane (neohexane). The normal hexane, a straight chain hydrocarbon, exhibits an octane number rating of 59, whereas the isomer 2,2-dimethyl butane or neohexane having a highly branched molecular structure demonstrates an octane number rating of 95.

A number of methods have been proposed for the manufacture of higher octane number hydrocarbons from those of lower octane number, such as alkylation, polymerization, and various other methods which have been widely used for the treatment of various hydrocarbon mixtures. An example of such a process is the production of iso-octane from isobutane and other saturated or unsaturated hydrocarbons by various thermal and catalytic means. A principal advantage possessed by the present process over other methods proposed for the improvement of hydrocarbon octane number is that through the use of catalysts and suitable selected conditions of temperature and pressure a feed stock which contains any combination of hydrocarbons in the natural gasoline range may be converted by a combination of integrated and mutually dependent and flexible treatments to other hydrocarbons of higher octane number which are suitable for use in aviation and/or motor fuels of premium grade in any desired proportion, thereby obtaining maximum octane number efficiency from charge stock of varying constitution.

The principal object of this invention is to

produce higher octane number normally liquid hydrocarbons from lower octane number normally liquid hydrocarbons in the natural gasoline range. It is specifically an object of this invention to provide a treatment for natural gasoline hydrocarbons to enable production of aviation gasoline and motor fuel of high octane number. It is thus possible to attain a high percentage recovery of hydrocarbons in the natural gasoline range of maximum efficiency for use in internal combustion engines. The process is of such flexibility that aviation gasoline and motor fuel may be recovered in any desired percentage limited only by the character of the charge stock.

15 Further objects and advantages of the invention will become apparent as the following description and disclosure proceed.

In accordance with this invention certain conditions of temperature and pressure are applied 20 to hydrocarbon charge stock, particularly natural gasoline, which result in the separation of a fraction comprising a material having characteristics desired for reformation into highly branched-chain aviation gasoline hydrocarbons. 25 A second heavier fraction composed principally of higher molecular weight straight-chain hydrocarbons is separated and catalytically dehydrogenated, according to the present invention. The light reformation stock is catalytically isomerized under controlled conditions for the recovery of a highly valuable aviation gasoline. A relatively high-boiling fraction of the isomerization effluent comprises essentially straight-chain hydrocarbons composed of unconverted hydrocarbons and a substantial percentage of higher molecular weight straight-chain hydrocarbons produced as the result of reforming reactions in the isomerization process. This fraction separated from the isomerization effluent combined 30 with the high-boiling fraction separated from the initial fraction of natural gasoline feed stock is subjected to catalytic dehydrogenation under such conditions that an extremely valuable high octane number motor fuel is recovered. Specifically, by the present invention the manufacture 35 of aviation and motor fuel of high octane number is accomplished through the application of a combined catalytic isomerization and catalytic dehydrogenation process to a charge stock which 40 may contain any combination of hydrocarbons in the natural gasoline range in any concentration whatsoever.

Natural gasoline feed stock is subjected, in a primary separation step in the process, to fractionation under conditions so controlled that an

overhead fraction boiling from approximately 100 to 150° F. at a pressure of about 10 to 170 pounds per square inch is separated which includes a range of hydrocarbons in the natural gasoline range especially suited for improvement by the catalytic isomerization treatment herein-after described. These materials advantageously comprise hydrocarbons containing from four to seven carbon atoms to the molecule, and include butanes, pentanes, hexanes, heptanes, and similar materials which on reformation will meet high octane requirements for aviation gasoline. A heavier fraction separated in this step comprises the raw feed stock to the dehydrogenation process. The lighter hydrocarbon fraction so separated is subjected in the presence of a suitable catalyst such as one of the metallic halides, particularly aluminum chloride carried on a satisfactory supporting material, and in the presence of hydrogen chloride, to pressure and temperature conditions of the order of from 0 to 500 or more pounds per square inch and 0 to 1000° F., respectively. These conditions are so maintained and controlled that decomposition reactions are slight, and ordinarily less than 10%, preferably less than 5%, of the charge stock in this step undergoes splitting reactions. The isomerization reaction is favored considerably if the temperatures which are used in conjunction with a reasonably high pressure are maintained well below those at which decomposition usually begins. Therefore, for isomerizing I prefer temperatures of about 200 to 700° F. and pressures of the order of 50 to 300 pounds per square inch.

Isomerization is accompanied by the formation of substantial amounts of higher molecular weight straight-chain hydrocarbons in addition to highly branched-chain structures. This is illustrated in the isomerization of butane to isobutane in which substantial quantities of butane are alkylated to pentane and materials of higher molecular weight.

Following the isomerization treatment, suitable means such as a fractionating tower are employed to separate the highly-branched-chain aviation hydrocarbons from heavier material, ordinarily predominately straight-chain hydrocarbons, formed during the isomerization reaction, and the latter material is subjected to catalytic dehydrogenation in admixture with relatively high-boiling material from original raw feed stock as heretofore described. This combined feed with insufficiently reacted recycle stock from a later stage in the process is subjected in the presence of a suitable catalyst such as chromic oxide gel, chromic oxide carried on a suitable support, or bauxite, to reaction pressure and temperature conditions of the order of 0 to 100 or more pounds per square inch and 600 to 1200° F., respectively. These conditions are carefully maintained so that not more than 30% of the total feed stock is converted per pass through the reaction zone. The suitable, exact conditions generally depend upon the type of feed stock and the catalyst used and are best determined by trial. Separation steps are now employed which result in isolation of hydrocarbons in the motor fuel range from lighter material which is either removed from the system or recycled, and heavier material which is preferably recycled through the dehydrogenation step.

The process of this invention may be carried forward in equipment such as shown in the drawing which is a diagrammatic side elevation of the various processing elements, not drawn to

scale, and illustrates one means by which the process may be practiced.

By reference to the drawing, a natural gasoline feed stock as heretofore described is introduced through conduit 1 and compressed to a suitable pressure by means of pump 2 for entry into separation element 4 by way of conduit 3. The hydrocarbons in the aviation fuel range pass through conduit 5, condenser and cooler 6, and into accumulator 8 via conduit 7. A portion of the condensate is taken from accumulator 8 through conduit 9 and compressed by means of pump 10 to a pressure sufficiently high to introduce it through conduit 11 as a reflux or cooling medium near the top of 4. A quantity in excess of that required for this purpose is continuously removed from 8 through conduit 12. This material together with recycle stock which enters through conduit 62 is compressed to a suitable isomerization reaction pressure by means of pump 13. This pressure is between 0 and 500 or more pounds per square inch. The total feed then passes through conduit 14 and thence through heat exchanger 15 where a satisfactory isomerization reaction temperature is obtained by heat interchange with hot dehydrogenation catalyst chamber effluent products which are passing through conduit 80. Conduit 16 and valve 17 comprise the elements of a by-pass around 15 through which a portion of the isomerization feed is passed for the purpose of controlling the temperature of the feed. The preheated feed stock then passes into a suitable catalyst case 19 through conduit 18, together with light hydrocarbon vapors and hydrogen chloride which join this stream through conduit 55. In the catalyst case the natural gasoline hydrocarbons are subjected to the influence of a suitable catalyst such as one of the metallic halides. The reaction temperature is such that the decomposition of the hydrocarbons so treated will be less than 5 per cent by weight for reaction periods which may vary from about 5 to about 30 minutes, the most suitable exact conditions being determined by trial. Conditions may be maintained to vary the composition of the equilibrium mixture of reaction products in accordance with the type of product desired.

Following passage through the reaction zone, the hot reaction products pass via conduit 20 into exchanger 21 where they are cooled by suitable means prior to entry into separation element 25 through pump 21-A and conduit 24. Conduit 22 and valve 23 constitute a by-pass through which a portion of the reaction products may be passed for temperature control. Hydrocarbons lighter than those desired in aviation fuel together with hydrogen chloride pass through conduit 26, condenser and cooler 27, conduit 28, and into condensate accumulator 29. A portion of the condensate is taken from accumulator 29 through conduit 30 and compressed by means of pump 31 to a pressure sufficiently high to permit its introduction as a reflux or cooling medium near the top of 25 via 32. One portion of a quantity in excess of that required for this purpose is continuously removed from the system as a liquid through conduit 33, valve 34, and conduit 35. A second portion of the quantity in excess of that required for this purpose and which contains an appreciable concentration of hydrogen chloride is removed as a vapor near the top of 29 and passes through conduit 53, pump 54, and conduit 55 to its point of juncture with the hot catalyst chamber feed. Fresh hydrogen chloride make-up

is provided by means of tank 58 and conduit 57. The bottom product which contains the valuable aviation fraction, together with insufficiently reacted material and some heavier hydrocarbons which were formed in the reaction zone, passes through conduit 36 into a neutralization contactor 37 where a material such as caustic soda is employed for the purpose of neutralizing or removing a small quantity of hydrogen chloride. Thence the hydrocarbons and neutralizing solution pass through conduit 38 and into a settling tank 39 where the hydrocarbons are separated from the neutralizing solution and pass through conduit 44 into separation element 45. Conduit 41, pump 42, and conduit 43 permit recirculation of the partially used neutralizing solution. Fresh solution is introduced through conduit 40, and spent solution is removed from the system through valve and conduit 41-A and 41-B. The aviation fuel constituent passes through conduit 45, condenser and cooler 47, conduit 48, and into condensate accumulator 49. As in the preceding step, a portion of this material is introduced near the top of 45 by means of conduit 50, pump 51, and conduit 52, to act as reflux or cooling medium. The valuable constituent in excess of the amount required for this purpose is removed from the system through conduit 60, pump 61, conduit 62, valve 64, and conduit 65. A portion of this material, however, is recycled to the system through conduit 62, for the purpose of reaction control. The bottom product which consists of hydrocarbons of higher molecular weight passes through conduit 57, pump 58, and conduit 59 into dehydrogenation feed tank 69 together with dehydrogenation recycle stock from conduit 118. Here these two streams are mixed with raw feed which has entered through conduit 66, pump 61, and conduit 68.

The combined feed to the dehydrogenation system passes through conduit 70 into pump 71 where it is compressed to a suitable reaction pressure. This pressure is between 0 and 100 pounds or more per square inch. The total feed then passes through conduit 72 and thence through heat exchanger 73 where a certain temperature is obtained by heat interchange with hot catalyst chamber effluent products which are passing through conduit 79. The partially heated feed then passes through conduit 74 into a heating coil 75 which is enclosed in a suitable furnace or heating means 76. The preheated hydrocarbons (600° to 1200° F.) then pass via conduit 77 into a suitable catalyst case 78 where they are subjected to the influence of a suitable dehydrogenation catalyst such as one of those heretofore described. The reaction temperature is such that the conversion of the hydrocarbons so treated will be not more than 30 per cent by weight for reaction periods corresponding to flow rates which may vary from 1½ to 3 volumes of liquid feed per volume of catalyst per hour, the most suitable exact conditions being determined by trial.

Following passage through the reaction zone, the hot reaction products exchange heat in turn with the cold dehydrogenation feed passing through exchanger 73 and the cold isomerization feed passing through exchanger 15. Thence they pass through conduit 81, cooler 82, and conduit 83 into separation element 84. Hydrogen and lighter hydrocarbons together with some of the heavier hydrocarbons pass overhead through conduit 85, pump 86, conduit 87, condenser and cooler 88, and conduit 89 into separation element 80.

The pressure and temperature obtained by means of pump 86 and condenser and cooler 88 are such that a satisfactory separation is obtained in 80 between ethane and lighter hydrocarbons containing the hydrogen, and butane and heavier hydrocarbons. These lighter hydrocarbons containing the hydrogen can be continuously removed from the system through conduit 91, valve 92, and conduit 93. However, it is considered to be essential for proper control of the dehydrogenation reaction to recycle a certain portion of the stream containing hydrogen through conduit 12. This is accomplished by the provision of a juncture of line 91 with line 12. The bottom product from 84 passes through conduit 94 into pump 95 where it is compressed to a pressure sufficient for entry, together with the bottom product from 90 which is passing through conduit 97, into separation element 98 through conduit 96. Hydrocarbons which are essentially butane in composition pass through conduit 99, condenser and cooler 100, conduit 101, and into condensate accumulator 102. A portion of the condensate is introduced near the top of 98 by means of conduit 103, pump 104, and conduit 105, as a reflux or cooling medium. The quantity in excess of that required for this purpose is continuously removed from the system through conduit 106. The bottom product passes through conduit 107 into separation element 108 where the motor fuel fraction passes through conduit 109, condenser and cooler 110, conduit 111, and into condensate accumulator 112. A portion of the condensate is taken from the accumulator 112 through conduit 113 and compressed by means of pump 114 to a pressure sufficiently high to introduce it as a reflux or cooling medium near the top of 108 via conduit 115. The motor fuel fraction in excess of that required for this purpose is removed from the system through conduit 116, pump 117, valve 118, and conduit 120. However, it is considered to be desirable to recycle a portion of this material to the system for control. Provision for this recycling operation has been made through the juncture of conduit 118 with conduit 59. A hydrocarbon fraction boiling above the motor fuel range is removed from separation element, or fractionator, 108 as a bottom product through conduit 121.

The motor fuel fraction which results from the foregoing procedure constitutes a highly valuable product of greatly improved octane number. The economies of the process are evidenced in the fact that this highly improved fuel includes hydrocarbons not amenable to the isomerization treatment as well as those of higher molecular weight formed thereby which are thus sufficiently improved in octane number to meet premium motor fuel requirements.

I claim:

1. A process of producing high octane number hydrocarbons from relatively low octane number hydrocarbons in the natural gasoline range which comprises separating from natural gasoline feed stock a relatively low-boiling fraction boiling from about 100 to 150° F. at a pressure of about 10 to 170 pounds per square inch, separating a relatively higher-boiling fraction from said feed stock, catalytically isomerizing said low-boiling fraction at a temperature of about 200 to 700° F. and recovering from the isomerization effluent a fraction consisting essentially of high octane number branched-chain hydrocarbons suitable as aviation gasoline components

and a further fraction substantially composed of straight-chain hydrocarbons, combining said last mentioned fraction with said relatively higher-boiling fraction from said natural gasoline feed stock, catalytically dehydrogenating said combined fractions, and recovering high octane number motor fuel from the dehydrogenation effluent.

2. A process of producing high octane number hydrocarbons from relatively low octane number hydrocarbons in the natural gasoline range which comprises separating from natural gasoline feed stock a relatively low-boiling fraction boiling from about 100 to 150° F. at a pressure of about 10 to 170 pounds per square inch, separating a relatively higher-boiling fraction from said feed stock, catalytically isomerizing said low-boiling fraction by contacting same with a metallic halide in the presence of hydrochloric acid and at a temperature of about 200 to 700° F. and recovering from the isomerization effluent a fraction consisting essentially of high octane number branched-chain hydrocarbons suitable as aviation gasoline components and a further fraction substantially composed of straight-chain hydrocarbons, combining said last mentioned fraction with said relatively higher-boiling fraction from said natural gasoline feed stock, catalytically dehydrogenating said combined fractions, and recovering high octane number motor fuel from the dehydrogenation effluent.

3. A process of producing high octane number hydrocarbons from relatively low octane number hydrocarbons in the natural gasoline range which comprises separating from natural gasoline feed stock a relatively low-boiling fraction boiling from about 100 to 150° F. at a pressure of about 10 to 170 pounds per square inch, separating a relatively higher-boiling fraction from said feed stock, catalytically isomerizing said low-boiling fraction and recovering from the isomerization effluent a fraction consisting essentially of high octane branched-chain hydrocarbons suitable as aviation gasoline components and a further fraction substantially composed of straight-chain hydrocarbons, combining said last-named frac-

tion with said relatively higher-boiling fraction from said natural gasoline feed stock, catalytically dehydrogenating said combined fractions, and recovering high octane number motor fuel from the dehydrogenation effluent.

4. A process of treating natural gasoline which comprises fractionating a natural gasoline feed stock and isolating a fraction boiling from about 100 to 150° F. at a pressure of about 10 to 170 pounds per square inch, separating a relatively higher-boiling fraction from said feed stock, catalytically isomerizing said first mentioned fraction under such conditions that less than 10% of the charge stock undergoes splitting reaction, 15 separating from the isomerization effluent a fraction consisting essentially of high octane branched-chain hydrocarbons suitable as aviation gasoline components and a further fraction consisting substantially of straight-chain hydro- 20 carbons, combining said last-named fraction with said higher-boiling fraction from said natural gasoline feed stock, and subjecting said combined fractions to catalytic dehydrogenation.

5. A process of treating natural gasoline which 25 comprises fractionating a natural gasoline feed stock, isolating a fraction boiling from 100 to 150° F. at a pressure of from 10 to 170 pounds per square inch, separating a relatively higher-boiling fraction from said feed stock, catalytically 30 isomerizing said first fraction under such conditions that less than 10% of the charge stock undergoes splitting reactions, separating from the isomerization effluent a fraction consisting essentially of high octane branched-chain hydro- 35 carbons suitable as aviation gasoline components and a further fraction consisting substantially of straight-chain hydrocarbons, combining said last-named fraction with said higher-boiling fraction from said natural gasoline feed stock, 40 and subjecting said combined fractions to catalytic dehydrogenation under such conditions that not more than 30% of the total feed is converted per pass through the reaction zone.
